UNITED STATES PATENT OFFICE.

EDWIN A. PACKARD, OF YONKERS, NEW YORK, ASSIGNOR TO INTERNATIONAL COMBUSTION ENGINEERING CORPORATION, OF NEW YORK, N. Y., A CORPORATION OF DELAWARE.

BOILER FURNACE.

Application filed November 3, 1925. Serial No. 66,442.

- This invention relates to boiler furnaces and it has for its primary object the provision of a novel, compact arrangement of boiler furnace occupying a minimum of 5 both ground area and height, whereby initial plant investment is greatly reduced and steam generated with a unit much smaller than at the present time required in standard practice.
- 10 Another object of the invention is to provide a boiler-furnace of the characteristics described by virtue of which the remainder of the installation,—particularly where the fuel used is in the form of pulverized coal—15 can be conveniently accommodated in a small building.

Other and more specific advantages and objects will appear hereinafter.

The foregoing, together with such other 20 objects as may hereinafter appear, are obtained by means of a construction which I have illustrated in preferred form in the accompanying drawings, wherein

Fig. 1 is a horizontal section thru a boiler-25 furnace embodying my improvements;

Fig. 2 is a vertical section thru the boiler-furnace of Fig. 1, and

Figs. 3 and 4 are views similar to Figs. 1 and 2, but illustrating a modification of the 30 invention.

Referring now to the arrangements of Figs. 1 and 2, it will be seen that I have provided a furnace, the combustion space of which is very largely defined by tubes subjected to radiant heat. The furnace is somewhat horse-shoe shaped in cross section, the rear portion of the combustion space being defined by a bank of vertical boiler tubes 7 connected to the upper and lower drums 8 and 9 respectively, the sides and the front being formed by vertical tubes 10. On the outside of the tubes 10 is a refractory or other suitable form of shell 11, the top of the combustion space being closed by refractory roof 12. Beneath, is, a refractory ash pit 13.

A horse-shoe shaped header 14 leads from the drum 9 around the outside of the pit 13 to a point just short of the drum 9, this header 14 lying somewhat below the shell 11. The tubes 10 rise upwardly from this header 14 to a similar header 15, this header, however, connecting with the upper drum 8 at the opposite end and extending around 55 the roof 12 to a point just short of the drum

8. This header lies above the shell 11, whereby straight tubes 10 may be employed.

The tubes 7 are baffled so as to provide a plurality of passes. The circulation is from the lower drum to the upper drum thru 60 those rows of the tubes 7 nearest the source of greatest heat and thence downwardly thru those rows of tubes 7 removed from the source of greatest heat. Circulation also takes place from the drum 9 around thru 65 the header 14 and thence upwardly thru the tubes 10 to the header 15 and around such header into the drum 8. It will be noted that the connection of the header 14 to the drum 9 and of the header 15 to the drum 8 70 is such that the distance to be traversed is the same thru all of the tubes 10, whereby short circuiting with possible burning out of tubes is prevented.

The powdered coal is admitted thru one 75 or more burners 16, preferably with all of the air required for combustion and with the air and coal intimately mixed so as to form turbulent combustion with a short hot flame, combustion being approximately completed before the first pass is reached. The flame is thus essentially a vertical one and the refuse particles of combustion are thrown down into the ash pit, these precipitating particles passing thru a water screen 80 formed of spaced tubes 17 connected into the circulation of the boiler and operating to cool such refuse particles below slag forming temperature, whereby the particles remain in individual form capable of ready 85 removal. The tubes 17 are connected at the rear to a header 18 and at the front to a header 19. Certain of the downcomer tubes of the bank of tubes 7 are carried down thru the drum 9 to the header 18. Up- 90 comers 20 lead from the header 19 to the drum 8 so that circulation takes place thru the screen in the direction indicated by the arrow.

The fuel being burned turbulently, the 100 furnace temperature is proportionately high and heat is absorbed by the radiant heat tubes at a very high rate, in consequence of which a large quantity of steam is produced with but a small portion of the tubes now 105 required to produce the same quantity of steam. The flame also being short, the vertical height of the boiler-furnace is cut down.

Referring now to the construction of Fig. 110

3 and Fig. 4 this is in all essential respects the same as that already described. In this case, however, the upper header 15^a has neither end connected with the drum 8. 5 This header is divided in the middle by a division plate 21. From either side of the division plate 21 a pipe 22 leads to the drum 8. Circulation is, therefore, thru the header 14, the tubes 10, the two halves of the header 10 15^a and the pipes 22, the water and steam having to travel the same distance thru all tubes 10.

The water screen in this case inclines oppositely, downcomers 20^a leading to the 15 header 19, the rear header 18 being dispensed with and the tubes 17^a being connected to upcomer tubes of the bank of tubes 7.

What I claim is:

- 20 1. In combination, a horse-shoe shaped boiler-furnace, an upper and a lower drum, a horse-shoe shaped upper header and a lower header of the same shape, one end of the upper header being connected to the 25 upper drum and one end of the lower header being connected to the lower drum, tubes connecting the two headers and defining the

front and sides of the combustion space of the furnace, and tubes connecting the drums, said latter tubes defining the rear of the 30 combustion space.

2. In combination, a horseshoe shaped boiler furnace, an upper and lower drum, horseshoe shaped upper and lower headers connected to the upper and lower drum respectively, tubes connecting the two headers and defining the front and sides of the combustion space of the furnace, and tubes connecting the said drums, said latter tubes defining the rear of the combustion space. 35

3. In combination, a horseshoe shaped boiler furnace, an upper and lower drum, a horseshoe shaped upper header and a lower header of the same shape, one end only of the upper header being connected to the upper drum and the opposite end only of the lower header being connected to the lower drum, tubes connecting the two headers and defining combustion space of the furnace and tubes connecting the upper and lower 40 drums. 45

In testimony whereof, I have hereunto signed my name.

EDWIN A. PACKARD.
